UNITED STATES PATENT OFFICE

JAMES W. HARVEY, OF FALMOUTH FORESIDE, MAINE

MARINE PROPULSION

Application filed May 16, 1930. Serial No. 452,942.

My invention relates to means for mounting motors in boats. The customary method of permanently installing motors or engines in boats is to mount the engine upon a foundation fixed in the bottom of the boat and to provide a propeller shaft running longitudinally and passing through stuffing boxes in the stern of the boat. Motors of this type are usually quite heavy and expensive and it is difficult to install or remove them. The stuffing boxes for the propeller shaft also occasion serious difficulties.

Another type of propulsion which has developed extensively for a comparatively small boat is what is commonly termed an "outboard motor" in which construction the motor frame is suspended or hung from the stern of the boat and a vertical drive shaft is geared to the propeller. This construction conveniently serves as a means for steering as well as driving the boat because of the facility with which the propeller can be turned from side to side. It has also been proposed to install a motor of this type in an open well in the bottom of the boat. Such constructions, however, materially weaken a boat and seriously impede or retard the speed of the boat due to the interference with the normal lines of the boat.

The main object of my invention is to provide a construction in which the so-called "outboard" type of motor can be readily installed in the boat in a position which is readily accessible for control and inspection and where the weight of the motor and the operator will not rock or tilt the boat into an unnatural position. I have especially sought to provide a convenient means for installing the motor so that it will be possible to obtain a maximum speed of the boat for the power developed by the motor. I have also sought to provide a construction from which the motor can be demounted or removed for the purpose of inspection, transportation and so forth. I accordingly provide in the bottom of the boat a casing which reinforces the bottom of the boat and is provided with top and bottom plates which serve as bearings for the housing of a vertical motor shaft on the upper end of which is

mounted the motor, and on the lower end the propeller. These plates are preferably connected together in the form of a framework which is guided in vertical walls of the casing for the purpose of insertion and removal. The bottom plate entirely closes the opening in the bottom of the casing and conforms in outline to the bottom of the boat. The protecting skeg may also be provided for automatically raising the motor and its propeller. Details of three forms of construction involving my invention are shown in the accompanying drawings.

Fig. 1 is a side view of a boat embodying my invention, parts being broken away and shown in section to illustrate the mounting of the power unit.

Fig. 2 is a transverse sectional view showing the method of supporting the power unit.

Fig. 3 is a perspective view of the casing constituting the mounting for the power unit.

Fig. 4 is a longitudinal sectional view showing a modified form of construction.

Fig. 5 is a longitudinal sectional view showing another modified form of construction.

Fig. 6 is a plan view of parts of this modification.

Fig. 7 is a detail of another modification.

The invention is applicable to boats of substantially any design and the power unit may be located at any point desired. The power unit itself is susceptible of embodiment in any suitable form having a vertical shaft within a housing 7 and geared at the lower end to a propeller 8. The casing 9 is preferably formed of a casting which is commonly termed "marine bronze" or other material having sufficient strength and resistance to corrosion. This casing is inserted upwardly through an opening in the bottom of the boat so that its upper edge projects above the load water line and it has a flange 10 which is preferably secured in place by an inner plate 11 and a series of bolts 12 so that the edges of the opening in the bottom of the boat are securely clamped between the flange 10 and the plate 11. The bottom plate 14 of the casing has its edges supported by an inner flange 15. The top or cover 16 of the casing is supported at its periphery in a groove 17 in the top of

the casing. A bottom plate 14 has a bearing 18 for the sleeve or housing 7 and the upper plate 16 has a bearing 19. These plates 14 and 16 and their bearings are adapted to support the entire weight of the power unit 6.

In the form shown in Figs. 1, 2 and 3 the bottom plate is formed in two parts secured together by bolts 20 which pass through lugs 21 and the top plate may be similarly formed for convenience in assembly. I also prefer to provide corner bars 22 which connect the upper and lower plates and thus form a framework which is guided in the corners of the casing.

15 In some motor units the motor exhaust is carried out through the vertical housing 7 and discharged immediately above the propeller. In other cases as herein shown the exhaust is discharged through a pipe 25. To provide for such a construction the top plate 16 has a central rotatable disc 26 through which the pipe 25 extends. The edges of this disc are supported in a bearing 27 so as to permit rotation of the power unit including 20 the exhaust pipe. The exhaust gases may pass out through an outlet 28 in the bottom of the casing or they may be let out through a side outlet 29 to any convenient point.

Ordinarily it will not be necessary to make 30 the bottom plate 14 tight in the casing because the water which leaks into the casing will be automatically sucked out through the discharge outlet 28 as soon as the boat is under way. In some cases the back pressure 35 from the motor will be sufficient to force the water out of the casing.

It should also be understood that any suitable form of cooling system may be employed for the motor and that this can be supplied 40 with water through the housing in the usual manner.

The power unit may be held in the casing in any suitable manner, as for instance, by means of spring clips 30.

45 I may also provide means for automatically lifting the motor in case the boat passes over an obstruction. For this purpose a skeg 31 is hinged at 32 to the bottom of the boat and adapted at its rear swinging end to engage a lifter plate 33 carried by the propeller housing 34. A stop 35 may be provided to limit the downward swing of the skeg.

The modified construction shown in Fig. 4 differs from that preceding in that the top bearing plate is made in sections 40 and 41 joined by hinges 42. Section 41 is hinged to the upper edge of the rear wall of the casing 9' at 43, and the rear wall 44 of the casing is curved upward and to the rear to 55 form a bearing surface on which the rear edge 45 of the bottom bearing plate can ride during the raising or lowering of the power unit and upon which this edge can rest when the power unit is in its fully retracted position.

60 65 The radius of the curve in the wall 44 is

greater than the distance between the hinges 42 and 43 so that an upwardly and rearwardly tilting action is produced as the power unit is retracted until it reaches the limit of rearward motion and a position in which it may readily be inspected and repaired. It is possible to submerge the propeller by simply swinging the top portion of the unit forward about the hinge 43 whereupon the bottom portion automatically slides down along the rear wall of the casing—and the bottom bearing plate automatically takes its proper seat and position.

With this construction a lifter of the type of 31 and lifter plate similar to 33 may be used to automatically retract the power unit in case the lifter strikes an obstruction.

It should be understood that the upper member including the parts 40 and 41 may be of a skeleton formation when it is not desired to confine the exhaust gases within the casing and that for convenience of installation in existing boats this type of casing may be made in sections to be applied from above and below the bottom of the boat and joined within the hull.

In Figs. 5 and 6 the power unit is supported by bearings carried by top and bottom plates 46 and 47 which are connected by rods 48 and 49. Casing 9" is substantially the same as that of the first form. In this construction, however, the top and bottom plates have sections 50 and 51 which are hinged to the casing at 52 and 53 so that they can swing upwardly and downwardly. These sections are hinged at 54 and 55 to the front edges of the rear portions of the top and bottom plates so that when the power unit is raised the lower part swings about the axis 53 and the upper part swings about the axis 52 producing an upward and forward tilting action as the power unit is retracted to the position shown dotted in Fig. 5. The result is that the power unit is held in position when retracted as well as when in working position. It is thus more convenient for inspection and repair. The unit thus has a definite retracted position and it is possible to submerge the propeller by simply swinging the power unit downwardly and to the rear whereupon it automatically takes its proper seat and position.

With such a construction a lifter 56 hinged at 57 to the bottom of the boat and provided with a stop 58 may engage directly with the bottom of the plate section 51 and automatically retract the propeller and motor in case the lifter strikes an obstruction.

It should be understood that the upper member including the parts 46 and 50 may be of a skeleton formation when it is not desired to confine the exhaust gases within the casing.

Fig. 7 shows a modified construction of the skeg 56' which may have an arm 59 ex-

tending in front of and below the propeller drive housing 60 as an additional protection for it, and is so proportioned that there is no interference with the upward movement of the power unit.

5 The size of the casings 9, 9' or 9" depend upon the size of the propeller and the other parts attached to the shaft housing, the intention being to permit the easy insertion and removal of the power unit without disturbing the casing.

10 By the use of this invention it is possible to employ a very substantial power unit even in a small size boat and still maintain stability and without occupying more than a minimum of the displacement of the boat. The construction lends itself naturally to installation between bulk heads such as 36 and 37 where it can be entirely covered by hatches 20 such as 38. The steering gear may have an external wheel 39 above the hatch or the motor can be turned by the use of cables and a remote steering gear, as is customary in other constructions.

25 While I have particularly intended the invention for a typical inboard motor which is used not only for forward propulsion but for steering as well, it should be understood that the use of a separate rudder might have 30 advantages in some cases. I therefore wish it understood that the claims are to be construed broadly within the spirit of the invention as herein set forth.

I claim:

25 1. A boat having an opening in the bottom, a reinforcing casing extending upwardly through said opening and having a flange beneath the edge of the opening, means for clamping the flange to the bottom of the boat 40 and a power unit adapted to be inserted into said casing including a vertical shaft housing and a bottom bearing plate adapted to substantially close the bottom of the casing, said power unit and bottom plate being removable from said casing.

50 2. A boat attachment comprising a reinforcing casing adapted to the bottom of a boat and open at the top and bottom, and a power unit having a shaft housing with a motor on one end and a propeller on the other end and bearing plates on the shaft housing movably supported as a unit at and substantially closing the top and bottom of the casing.

55 3. A boat attachment comprising a reinforcing casing adapted to the bottom of a boat and open at the top and bottom, and a power unit having a shaft housing with a motor on one end and a propeller on the other end and bearing plates on the shaft housing movably supported as a unit at and substantially closing the top and bottom of the casing, one plate having a rotatable disc with an opening for a pipe eccentric to the shaft 60 housing.

4. A boat having a casing secured in the bottom and open at the top and bottom, a movable power unit comprising a vertical shaft housing and a bearing plate secured to the housing and closing the bottom of the casing, a longitudinal motor lifter hinged to the bottom of the boat ahead of the casing opening and extending to the rear and having a portion at its rear end so disposed that it will move the power unit upwardly.

70 5. A boat having an opening in the bottom, a reinforcing casing extending upwardly through said opening and having a flange beneath the edge of the opening secured to the bottom of the boat and a power unit adapted to be inserted into said casing including a vertical shaft housing, a bottom bearing plate adapted to substantially close the bottom of the casing and a top bearing frame, said power unit, bottom plate and bearing frame being removable from said casing.

75 6. A boat having a casing secured in the bottom and open at the top and bottom, a removable power unit comprising a vertical shaft housing with a horizontal motor lifter bearing plate secured to the shaft housing and two bearing plates for the top and bottom of the casing, a longitudinal motor lifter hinged to the bottom of the boat ahead of the casing opening extending to the rear and having a portion at its rear end so disposed that in its upward travel it will raise the motor lifter bearing plate and move the power unit.

80 7. A boat attachment comprising a casing adapted to the bottom of a boat, a power unit having a frame with a bottom plate fitting in said casing, a hinged support connecting the casing and said power unit and a second hinged member connecting said power unit to said casing and acting as a support for an edge of said bottom plate in 85 partially or fully retracted positions.

85 8. A boat attachment comprising a casing adapted to the bottom of a boat, a power unit having a frame with a bottom plate fitting in said casing, a hinged support connecting the casing and said power unit, said casing having an upwardly and outwardly curved wall in said casing acting as a support for the 90 rear edge of said bottom plate in partially or fully retracted positions, the radius of the curved portion of said casing being greater than the distance between hinge pin centers of said hinged support connecting the upper 95 edge of said casing and said power unit, so that the power unit tilts longitudinally to the rear as it is lifted in the casing.

100 9. A boat attachment comprising a casing adapted to the bottom of a boat and open at the top and bottom, a power unit having a frame with a bottom plate fitting in and closing the bottom opening in said casing and a hinged support connecting the casing and the 105 110 115 120 125 130

power unit frame whereby the power unit is tilted as it is raised.

10. A boat attachment as set forth in claim 9 having a hinged connection for the bottom plate.

11. A boat attachment as set forth in claim 10 having a longer radius for the hinged connection of the bottom plate so that the power unit tilts longitudinally as it is lifted in the casing.

10 12. A boat having a casing secured in an opening in the bottom and open at its top and bottom, a removable bottom plate closing the bottom opening, a power unit having a vertical shaft housing supported in the bottom plate and having a propeller removable upwardly therewith through the casing, the bottom plate having a water outlet discharging rearwardly aft the propeller.

20 13. A boat having a casing secured in the bottom and open at the top and bottom, a movable power unit having a bearing frame movable in the casing with a plate removably closing the bottom of the casing and having a water outlet opening in its rear edge, said power unit having a propeller operable forward of said outlet opening.

30 14. A power boat casing adapted to be secured in the bottom of a boat and open at the top and bottom and a removable power unit comprising a vertical shaft housing and divided bearing plates clamped on the housing and closing the top and bottom of the casing.

35 15. A boat attachment comprising a casing open at the top and bottom and a power unit having a propeller and a supporting frame movably mounted in the casing and having a bottom plate fitting the bottom of the casing, a member hinged at one end to the casing near the bottom and at the other end to the bottom plate to guide the propeller upwardly and other guiding means for the upper part of the supporting frame.

45 16. A boat having a casing secured to the bottom and open at the top and bottom and having a movable bottom plate and a movable top bearing frame, a power unit having an exhaust passage through the top frame, a vertical shaft housing supported in the bottom plate and having a propeller movable upwardly therewith in the casing.

50 17. A boat attachment comprising a casing adapted to the bottom of a boat, a power unit having a frame with a bottom plate fitting in said casing and a hinged member connecting the upper edge of the casing and said power unit, said casing having an upwardly and outwardly curved wall to guide the power unit into a tilted position in said casing as it is lifted.

JAMES W. HARVEY.
